(57) **CLAIM**

The ornamental design for an airplane window control switch, as shown and described.

DESCRIPTION

FIG. 1 is a front view of an airplane window control switch showing our new design, in a usage condition at the bottom of an airplane window;

FIG. 2 is a front perspective view thereof;

FIG. 3 is a front view thereof;

FIGS. 4 to 7 are front views thereof, showing various operating settings; and,

FIG. 8 is a front view of thereof, in a usage condition at the top of an airplane window.

The broken line shown in the figure drawings is included for illustrative purposes only and forms no part of the claimed design.
